UNITED STATES PATENT OFFICE.

CHARLES BURTON WINZER, OF BALHAM, LONDON, ENGLAND.

APPARATUS FOR CARBONIZATION.

Application filed December 21, 1925, Serial No. 76,757, and in Great Britain January 14, 1925.

This invention relates to the carbonization of coal, peat, wood, shale and the like and has for its chief object to provide a circular or straight oven in which the process of carbonization can be carried out continuously and in an efficient and expeditious manner.

According to the present invention the carbonizing chamber comprises a closed fire-proof muffle, and the flames or heating gases are caused to travel around the entire exterior of this chamber in a zig-zag or tortuous manner so that all parts of the chamber are effectively and properly heated and the process of carbonizing consists in conveying the material to be treated through the chamber in containers, or in basket-like carriers which are moved from the inlet or cold portion of the chamber, by successive steps of advance to the hottest part thereof and thereafter pass to a cooler portion where the carbonized material having given up or parted with the volatile and liquid by-products is moved or transferred to a cooling or collecting chamber.

As the carriers are advanced within this muffle or carbonizing chamber, the liquid contents such as oils or tars are extracted and are directed into collecting channels and can be drawn off by pipes or tubes. The volatile substances as they come off at different temperatures and points within the chamber, are drawn off by fans or other suitable extracting devices and may be conveyed direct to distilling or other apparatus.

The flues through which the flames or heating gases from the furnace or other source or sources of heat are caused to travel surround the closed muffle or carbonizing chamber in such a manner that the gases ascend through one or more flues, pass through one or more connecting flues at the upper side of the muffle and then descend by one or more flues to the lower side of the muffle; thereafter ascending and descending alternately until they are finally discharged to a chimney. These heating gases are thus caused to play all around the muffle or carbonizing chamber.

Referring to the accompanying drawings—

Fig. 1 is a part sectional plan view of a convenient form of circular apparatus embodying, or constructed in accordance with, the present invention.

Fig. 2 is a vertical cross-section of Fig. 1.

Fig. 3 is a detail sectional view drawn to a larger scale than Figs. 1 and 2 showing the carriers and a convenient method of charging them.

60

Fig. 4 is a view similar to Fig. 3 showing a convenient method of discharging the carriers.

Fig. 5 is a detail sectional view showing a convenient arrangement of ball bearings. 65

Fig. 6 is a horizontal sectional view of the ball-bearing shown in Fig. 5.

Fig. 7 is a vertical section of a straight form of apparatus and

Fig. 8 is a horizontal section of the apparatus shown in Fig. 7. 70

The process according to the present invention may be carried out in either a circular or in a straight apparatus. In all cases the material is passed in successive 75 steps or stages through a closed oven or chamber around part of which the heating gases are caused to pass, the material being conveyed to the hottest part of the oven, then to a cooler part and finally to a discharging position while the liquid and the volatile contents are extracted at successive stages of advance.

A circular form of apparatus will first be described. 85

This apparatus as shown in Figs. 1 to 5 comprises a closed and continuous fire-proof chamber or oven A within which is mounted a rotatable platform or table B which is formed of suitably constructed open or skelton sections or segments b of cast iron or other suitable material bolted or otherwise connected together.

This platform is preferably rotated by a suitable number of driving wheels or pinions B' adapted to gear or mesh with a circular rack or teeth B² formed on or carried by the rotatable platform around its inner edge.

The platform B is mounted upon ball or 100 roller bearings B³, B⁴ arranged to support the platform at its inner and outer circumferences respectively.

The inner bearings B³ are conveniently placed between annular races formed respectively on the upper surface of a rail or bar B⁵ and the lower surface of the platform.

The outer bearings may be similarly constructed, but preferably they are arranged at spaced intervals and each comprises a 110

series of balls mounted in a circular race B⁶ (see Figs. 5 and 6) which is fitted with an inclined or raised surface B⁷ situated immediately under the platform, so that as the 5 balls travel around the race and come under the platform they are raised, and only the balls so raised for the time being form the support for the platform B. A cover B⁸ is provided at the opposite side of the race B⁶ to that at which the balls are raised by the inclined surface B⁷.

The carriers C may be in the form of open cages or baskets when used for producing carbonized material in small pieces, or they 15 may, as shown, be open at top and have an openable lower end. The walls in such cases are solid or closed and they are tapered as shown, so that carbonized material may be discharged readily when in a mass or in a 20 larger piece or pieces. These carriers or containers are secured in any appropriate manner to the platform B and are open at top. At their lower ends the carriers are furnished with doors or flaps C' which are 25 hinged to one side of the carriers at c and at the other side are furnished with wheels c' adapted to run on suitable tracks until the carriers reach the discharge position. These flaps normally fit into openings in the platform B or in false, lattice or other bottoms 30 fitted to the cages, so that at the discharge position the flaps are opened automatically to allow the contents of the carriers C to drop into a cooling or collecting chamber A². 35 The apparatus may be provided with one or more furnaces or heaters. In the embodiment illustrated, two such furnaces D, D', are shown. The heating gases or products of combustion from these furnaces are 40 caused to travel around the entire carbonizing chamber proper or that part of the oven which constitutes the carbonizing chamber (see Figs. 1 and 2).

These heating gases pass through flues A' 45 in a somewhat zig-zag or tortuous fashion and the flues may be arranged singly or in parallel series. The heating gases from the furnace D' pass through a short flue a at the top of the furnace into a flue a' down which 50 they pass, and then through a horizontal flue a² at the bottom of the carbonizing chamber to an upgoing flue a³ at the other side, whence they pass through another short flue to the next downgoing flue a⁴ and so on. 55 The short passages or flues at top and bottom of the oven by or through which the gases pass to the up and down flues are preferably formed by placing a series of walls a⁵, a⁶ at intervals across the top and bottom of the chamber. Hence, the arrangement, in effect, 60 is such that a plurality of U-shaped or compound flues a¹—a²—a³ is provided, the middle portion a² of each of said flues being in the bottom wall of the chamber, and the 65 two limbs a¹ and a³ thereof being formed

vertically in the opposite side walls of said chamber respectively, said flues being connected in series.

When two furnaces are employed as shown the flues connected with the furnace D will alternate around the chamber with the flues of the furnace D'. In place of the gases being conducted through a single flue they may be led by two or more flues or passages arranged parallel with one another. In all 75 cases the flues or passages surround that part of the oven which forms the carbonizing chamber proper in such a manner that the gases play or act all around the walls of the carbonizing chamber to heat it equally all round.

The comparatively heavy iron platform B also acts as a heat conducting and radiating surface and increases the circulation of heat around the cages or carriers C thereby 85 tending to increase the efficiency of the apparatus.

These flues are continued around the carbonizing chamber as far as required and the spent gases and the like finally pass or are 90 discharged up a chimney E.

The charges of raw material are delivered to the cages or carriers C in succession during pauses between stops of advance. These charges are delivered from bunkers or 95 hoppers F arranged above a cold portion of the oven (see Figs. 2 and 3).

The bunkers or hoppers F are fitted with double doors F', F² arranged at top and bottom so that when the lower doors F² are 100 opened to charge the carriers the upper doors F' are closed so as to prevent any undue amount of cold air entering the oven or muffle.

The doors F' through which the hoppers 105 F are charged are preferably of hinged or flap type, while the lower doors F² are preferably of rotary or plug-cock type. Between each of the doors F² and the upper ends of the carriers C to be charged is arranged a pipe F³ which passes through the roof of the chamber A and terminates a 110 short distance above the upper ends of the carriers C.

In the arrangement illustrated provision 115 is made for charging three carriers simultaneously (see Fig. 3).

The cages C after being charged are moved in the direction of the arrow (Fig. 1) to the coolest part or end of the carbonizing chamber and thence pass by successive stages or steps to the hottest portion thereof around which the heating gases are circulated, then through a second cool portion and finally reach the discharge point G. 125

On reaching the discharge point the false bottoms of the carriers C are opened. This opening may take place automatically as above described or it may be accomplished mechanically by any suitable means. 130

The carbonized material falls from the carriers C into the previously mentioned cooling and collecting chamber A² which is situated below the level of the oven A, or 5 said material may fall into a trolley or truck H situated in this collecting chamber.

For convenience in removing the carbonized material from this chamber or from the trolley in this chamber, the chamber is 10 furnished with a door A³ which when closed cuts off communication between the oven A and the front or outer part of the collecting chamber A² so that when a door A⁴ at the outer end of the chamber A² is opened to 15 allow the truck to be withdrawn no undue quantity of air can enter the oven.

The doors A³ and A⁴ are normally closed. The door A³ normally extends transversely across the chamber A² dividing this chamber 20 into two parts each capable of receiving a truck. When a truck has been filled from the carriers the door A³ is withdrawn so that the truck can be moved from a position directly underneath the carrier into the 25 outer portion of the chamber A².

This door A³ is operated from a vertical shaft A⁵ which is geared to a horizontal shaft A⁶ which in turn is geared to a rack (not shown) on the door A³. When the 30 door A³ has been opened the truck H can be moved to the outer portion of the chamber A². This is accomplished by a shaft A⁷ one end of which is connected to or bears against the end wall of the truck H. This 35 shaft passes through one of the side walls of the oven and is geared to a vertical shaft A⁸ which can be turned by a hand wheel.

When the truck has been moved to the outer part of the chamber A² the door A³ 40 can be closed through the gearing A⁵, A⁶ thus cutting off communication between the outer portion of the chamber A² and the carbonizing chamber. The outer end of the chamber A² is normally closed by the door 45 A⁴ which is adapted to be raised and lowered, for which purpose it may be furnished with a counter-balance gear in a well known manner. When the door A⁴ has been raised the loaded truck H can be withdrawn. 50 By these means the carbonized material can be removed as it accumulates without interfering with the continuous carbonizing process in the oven or muffle.

The volatile by-products or substances of 55 the carbonizing process as they are evolved or given off as the carriers advance in the heated part of the chamber A rise to the upper part of the chamber and can be drawn off by one or more pipes or tubes such as I. 60 The liquid by-products are allowed to fall to the bottom of the chamber and can be collected and drawn off at various points by pipes such as J.

Referring now to the straight oven arrangement illustrated in Figs. 7 and 8, at 65

the inlet end of the oven there is situated a charging chamber A¹⁰ provided with an outer door A¹¹ through which the filled carriers C are introduced one at a time. This chamber A¹⁰ is situated at a lower level than 70 the carbonizing chamber A and the carrier is pushed on to an elevator K which can be raised by a shaft K' to lift the carrier to the floor level of the chamber A. Above this elevator and normally at the floor level 75 of the chamber A is a cover K² which prevents ingress of air to the chamber A when the door A¹¹ of chamber A¹⁰ is open. When a carrier C has been brought to the floor level of the chamber A it can be pushed into 80 the entrance of the chamber A by a sliding rod or pusher K³ and in being so pushed will force the carrier or carriers in front of it further into the chamber A.

The carriers as they are moved along the 85 chamber A pass from a cool portion to the portion where the temperature is gradually increased by the heating gases passing around passages or flues similar to those already described with reference to the circular arrangement. 90

The carriers C may be provided with wheels adapted to run along a track throughout the chamber A or they may be pushed into an endless track or platform carried 95 upon or geared to horizontal shafts.

At the exit end of the chamber A there is provided a discharge chamber A² which is preferably situated on the same level as the chamber A and is furnished with double doors A³ and A⁴ and carrier operating mechanism A⁷ similar to the corresponding chamber of the circular apparatus. 100

The charging chamber A¹⁰, in place of being below the level of the chamber A, may 105 be situated at the side of and on the same level as the chamber A and be furnished with double doors and carrier moving mechanism similar to those shown and described with reference to the discharge chambers. 110

Both in the circular and straight forms of apparatus the carbonizing chamber A is entirely closed and the process is carried out continuously, the raw material being inserted and the carbonized material withdrawn without permitting undue or detrimental quantities of cold air to enter. Also the furnace or heating gases are caused to play all around the exterior walls of the carbonizing chamber and by means of the arrangement of the flues or passages a uniform heat is obtained at the furnace and where the highest degree of temperature is necessary. At various points temperatures say from 80° to 500° C. may be obtained and regulated as necessary for evenly heating and penetrating the material thoroughly and for preventing caking, thereby ensuring that the extraction of the various by-products will be thorough. 120 125 130

What I claim is:—

1. In a carbonizing apparatus, a closed, horizontally elongated chamber having a pathway therethrough for material to be carbonized; said chamber being provided with a flue system comprising a plurality of U-shaped flues, each of which has its middle portion formed in the bottom wall of the chamber and its limbs formed vertically in the opposite side walls of said chamber respectively, said flues being connected in series; and a furnace for supplying hot gases of combustion to said flue system at one end thereof so as to travel in series therethrough.
2. Carbonizing apparatus, comprising a closed annular chamber having a vertical axis, the floor of said chamber having an aperture therethrough extending across the same; means for heating said chamber; an annular horizontal platform rotatably disposed within said chamber and spaced above the floor thereof; and a succession of vertically-elongated carriers mounted in said platform to contain material to be carbonized, said carriers projecting below the
3. In a carbonizing apparatus, a closed, annular chamber having a pathway therethrough for material to be carbonized; said chamber having a vertical axis and being provided with a flue system comprising a plurality of U-shaped flues, each of which has its middle portion formed in the bottom wall of the chamber and its limbs formed vertically in the opposite annular side walls of said chamber respectively, said flues being connected in series; in combination with a furnace for supplying hot gases of combustion to said flue system at one end thereof so as to travel in series therethrough.

In testimony whereof I affix my signature.

CHARLES BURTON WINZER.
